JUNIOR BOWLING GAME

Bruno Sekretarski, Milwaukee, Wis.

Application May 24, 1939, Serial No. 275,536

2 Claims. (Cl. 273—42)

The invention relates to a game apparatus and more especially to a home miniature bowling apparatus and pin setter.

The primary object of the invention is the provision of an apparatus of this character wherein a bowling game can be had within the home and the pins for the playing of the game can be readily and conveniently set or spotted, while the spent or played balls of a bowling game will be returned to players.

Another object of the invention is the provision of an apparatus of this character wherein the same is readily portable so that it may be set up within a home and a bowling game played in conformity with the rules and regulations for the playing of a regular or standard game and the pins can be set or spotted mechanically, thereby relieving an attendant of the hand setting or spotting of the pins.

A further object of the invention is the provision of an apparatus of this character which is simple in its construction, thoroughly reliable and efficient in operation, affording entertainment, being a miniature of a standard or regular bowling game set up and is inexpensive to manufacture.

With these and other objects in view, the invention consists in the features of construction, combination and arrangement of parts as will be hereinafter more fully described in detail, illustrated in the accompanying drawings, which disclose the preferred embodiment of the invention and pointed out in the claims hereunto appended.

In the accompanying drawings:

Figure 1 is a side elevation of the apparatus constructed in accordance with the invention and set up for use.

Figure 2 is a top plan view.

Figure 3 is a fragmentary sectional view taken on the line 3—3 of Figure 1 looking in the direction of the arrows.

Figure 4 is a fragmentary end elevation partly in section.

Figure 5 is a fragmentary perspective view partly in section of the apparatus.

Figure 6 is a fragmentary perspective view of the pin setter.

Figure 7 is a fragmentary perspective view of an adjunct of the pin setter.

Similar reference characters indicate corresponding parts throughout the several views in the drawings.

Referring to the drawings in detail, A designates generally the apparatus constructed in accordance with the invention being a miniature

edifice of a standard or regular bowling game set up and comprises a body frame 10 having the build of a bowling alley 11 open at one end and closed at the other. At this closed end is a pit 12. While the alley 11 is of elongated contour 5 there is following opposite longer side edges thereof gutters 13, these opening into the pit 12 so that when a bowling ball 14 is irregularly thrown or played in the alley 11 the said ball will travel into either of the gutters 13 to be 10 caught in the pit 12 for the retrieving thereof when playing a bowling game.

The alley 11 outermost of the gutters 13 is formed with the side walls 15, these joined with an end wall 16 at the closed end of said alley and 15 built with one of these side walls 15 is a ball return chute 17 for the return of the spent or played balls 14 to the players when stationed at the open end of said alley. Associated with the chute 17 next to the open end of the alley 20 11 is a post 18 carrying a chalk pocket 19 for the chalking of the hands of the players when effecting a bowling game.

The frame 10 has associated therewith foldable supporting legs 20, these when in supporting position are rigidly held through the use of break pivot joint braces 21 allowing the folding of the legs when the apparatus is not in use.

The alley 11 next to the pit 12 has a pin spotting or setting area 22 corresponding to that of 30 a standard or regular bowling alley, being on a miniature scale and at this area is spotted or set the bowling pins 23 for the playing of a bowling game.

Arranged at the area 22 of the alley 11 is a 35 pin setter comprising a horizontally disposed perforated pin setting rack 24 its perforations 25 being adapted to accommodate the pins 23 for the placement thereof perpendicularly in spotted or set up condition at the area 22. This rack is 40 rigidly supported by hanger arms 26 formed with and depending from an inverted substantially U-shaped raising and lowering yoke 27 bridging the alley with the side limbs 28 thereof outside of the side walls 15. These limbs 28 slidably fit 45 vertical guides 29 exteriorly on the side walls 15 and the upper portion of this yoke is formed with a hand grip or handle bar 30 so that the yoke may be raised or lowered and the rack 24 is in a raised position shown by dotted lines in 50 Figure 3 of the drawings after the pins 23 have been spotted or set in the area 22 of the alley 11.

One of the limbs 28 of the yoke 27 has formed therewith a latching extension 31 having the latching terminal 32 separably engageable with a 55

- spring keeper 33 fixed exteriorly on one side wall 15 in a position in the path of said terminal 32 and at an elevation to enable the rack 24 to be held in an elevated position with respect to the pins 23 when spotted or set in the alley at the area 22 thereof and thus eliminate any interference in the playing of a bowling game in the use of the apparatus. The terminal 32 can be readily operated from the keeper 33 by pressing 5 downwardly on the yoke 27 and thus lowering the rack 24 to a position for the spotting or setting of the pins 23, this position being in superimposed contacting relation to the alley 11 at the area 22.
- 15 The miniature apparatus before described enables home playing of a bowling game and the latter is played in conformity with a standard or regular game of this type. By the use of the pin setter a player or players can be designated 20 for the setting of the pins at the area 22, this being carried forth with dispatch and accuracy in such use.

It is of course understood that the alley 11 is marked with a foul line 34 to be observed by the 25 players for regulatory purposes.

While the yoke 27 has been illustrated as supported in elevated position by the latch bar 31 and the keeper 33 I do not intend to limit myself to this precise construction shown, the only limitation being that afforded within the scope of the appended claims. In the construction shown it should be observed that the limbs 28 of the yoke 27 are sufficiently elevated when the rack 24 is lowered to provide clearance with the bot-

tom of the frame 10, thus enabling the game to be operated when the legs 20 are folded beneath the table and the frame rests on the floor.

What is claimed is:

1. Apparatus of the kind described comprising a bowling alley structure, supports for said structure, a pin setting rack vertically movable within the bounds of said alley structure, a yoke carrying said rack, guides having the yoke fitted therewith, means for holding said yoke in elevated position above the alley, and means coacting with the yoke and the said rack to maintain the said yoke in a lowered position elevated from a floor line on the contact of the rack with the alley. 10

2. An apparatus of the kind described comprising a bowling alley structure having foldable supports, a pin setting rack movable within the bounds of said alley structure and including an inverted substantially U-shaped frame, vertical guides outside of the bounds of said alley structure and having side portions of said frame slidably fitted therein, yoke formed with the frame and depending within the bounds of said alley structure and constituting a suspension for the said rack from said frame, a latching extension carried downwardly from the upper portion of said frame outside of the bounds of said alley structure and having a latching terminal, and a spring keeper fixed without the bounds of said alley structure in the path of said latching terminal for the engagement of the latter therewith to hold the rack in an elevated position above the said alley. 20 30
